Borosilicate Triangle Capillary Glass Tubing and Rod. By Jinan Honhai Glass company. dated 2019. found online [Aug. 28, 2020] <https://honhai060306.en.made-in-china.com/product/CobxsGZKSNNAW/China-Borosilicate-Triangle-Capillary-Glass-Tubing-and-Rod.html>.*

Primary Examiner — Marissa J Cash*(74) Attorney, Agent, or Firm* — Mintz Levin Cohn Ferris Glovsky and Popeo, P.C.(57) **CLAIM**

The ornamental design for a vaporizer, as shown and described.

DESCRIPTION

FIG. 1 is a perspective view of a vaporizer showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines illustrate portions of the vaporizer that form no part of the claimed design.
